Patented Oct. 2, 1923.

UNITED STATES PATENT OFFICE.

JAMES A. NOLAN, OF BOWERSTON, OHIO.

FEEDING AND WEIGHING DEVICE.

Application filed April 25, 1923. Serial No. 634,617.

To all whom it may concern:

Be it known that I, JAMES A. NOLAN, a citizen of the United States, residing at Bowers-ton, in the county of Harrison and State of Ohio, have invented new and useful Im-
5 provements in Feeding and Weighing De-
vices, of which the following is a specifica-
tion.

This invention relates to feeders for use
10 in connection with mine cages or dumps, and
more particularly to a feeding and weigh-
ing device.

One of the main objects of the invention
is to provide simple and efficient means for
15 feeding loaded cars onto a dump, this means
being automatic in operation. A further ob-
ject is to provide means so constructed and
arranged as to weigh a car before the same
20 passes onto the cage or dump, this means
constituting a part of the feeding apparatus.
Further objects will appear from the de-
tailed description.

In the drawings:—

Figure 1 is a top plan view of the appa-
ratus as applied in connection with a ver-
25 tically movable cage;

Figure 2 is a section taken substantially
on line 2—2 of Fig. 1;

Figure 3 is a section taken substantially
30 on line 3—3 of Fig. 1;

Figure 4 is a section taken substantially on
line 4—4 of Fig. 1 showing the operating
arms on the fixed section of the approach
track in normal positions;

Figure 5 is a similar view showing the po-
sitions of the operating arms when the stops
35 are opened;

Figure 6 is a detail top plan view showing
the positions of the operating arms on the
40 fixed section of the approach track immedi-
ately after the trip lever has been operated
and the stops on the fixed section of the ap-
proach track have been closed;

Figure 7 is a diagrammatic view showing
45 how the apparatus can be applied to a rotary
dump.

The use of the apparatus will be described
in connection with a tilting dump, though it
will be understood that this apparatus can
50 be used equally well in connection with any
kind of a cage or dump such as a hoist or a
cage, or a rotary dump, a spiral dump, cross-
over dump, kickback dump, etc. While the
apparatus is intended more particularly to
55 be used for weighing the loaded cars as they
are fed onto the cage or dump, it can also be

used as a feeder without weighing of the
cars. The apparatus is illustrated as used in
connection with a dump A tiltably mounted
60 on a suitable support B, this dump being of
a known type and being provided with any
suitable or preferred means for stopping and
holding the cars on the dump. This does
not, however, form a part of my invention
65 except in so far as the dump co-operates
with the feeder apparatus to accomplish the
purpose desired. Dump A is provided with
the usual rail sections C which, when the
dump is in loading position, are disposed in
70 alignment with the rail sections of an ap-
proach track D which includes upper and
lower fixed sections E and F, respectively,
and a central movable section G which is
completely detached from sections E and F,
75 this central section G being mounted on a
structure forming a platform H which may
be connected to scales of any suitable type
in any suitable or preferred manner for
weighing a loaded car supported upon sec-
80 tion G. The approach track D is inclined
downwardly toward dump A, as is the usual
practice, for feeding the cars onto the dump
by gravity.

A main rock shaft 1 is rockably mounted
longitudinally of approach track D and is
provided, at its inner end, with a trip arm 2
from which projects a pin 3 which extends
85 through a bracket 4 carried by dump A.
This bracket is disposed in such manner as
to turn rock shaft 1 when the dump is tilted
for operating the feeder mechanism in a
90 manner to be disclosed.

An operating arm 5 is secured on the outer
end of shaft 1 and is normally positioned to
95 extend beneath an operating arm 6 secured
on a counter-shaft 7 rockably mounted in
bearing blocks 8 and 8^a on track section E.
This counter-shaft is normally held in one
longitudinal position by an expansion coil
100 spring 9 mounted about the shaft and con-
fined between bearing block 8^a and a collar
10 secured about the shaft. This collar is
provided with a radially disposed finger 11
through which is secured one end of a ten-
sion spring 12 the other end of this spring
105 being anchored to one rail of track section
E in any suitable or preferred manner. A
second collar 13 is secured on shaft 7 and is
provided with diametrically opposite arms
14 which are connected by links 15 to horns
110 or stops 16 rockably mounted on stub-shafts
17 supported in bearing blocks 18 secured

to the outer faces of the webs of the rails of track section E, these horns being mounted for sliding movement on shafts 17 and cushioned by coil springs 19 mounted about 5 the shafts. The horns and the mounting therefor and associated parts are well known in this art and need not be further described in detail. An angle trip lever 20 is rockably mounted, in any suitable or preferred manner, on track section E beyond or above the horns 16. The outer arm of this lever projects across the tread of the adjacent rail section so as to be displaced by the wheel of a car traveling down track section E. The 10 inner arm of lever 20 is connected by a chain 21 to a cap 22 secured on the outer end of counter-shaft 7, this cap also acting as a stop element for limiting movement of shaft 7 through bearing block 8^a in one direction. 15

20 A supplemental rocker shaft 22 is rockably mounted on track section G and is connected by links 23 and arms 24 to horns 25 similar to horns 16 mounted on the rail sections of track section E. A weight 26 is secured to shaft 22 and acts to normally rock this shaft in a direction to close stops 25. A control arm 27 is secured to shaft 22 and extends beneath a control arm 28 secured to rock shaft 1. 25

30 Return of dump A to loading position after dumping rocks shaft 1 in counter-clockwise direction as considered in Fig. 3. This brings arm 28 into contact with arm 27 depressing the latter and rocking shaft 22 in a clockwise direction opening horns 25 and raising weight 26. This releases a loaded car which was held on section G permitting this car to run onto dump A. When the loaded car runs onto the dump the dump 35 tilts into dumping position thus turning shaft 1, by means of bracket 4 and associated parts in the other direction. This rocks shaft 7, by means of arms 5 and 6, in stop opening direction opening stops 16 and permitting a loaded car to run onto track section G. The following loaded car rocks lever 20 pulling shaft 7 outwardly a sufficient distance to move arm 6 from directly 40 above arm 5 to the outer side thereof, thus releasing shaft 7 which is then rocked in stop closing direction by spring 12. This rocking of shaft 1 also serves to move arm 28 upwardly releasing arm 27 and permitting stops or horns 25 to be closed by weight 45 26. As will be noted more clearly from Figs. 4 and 5, arms 5 and 6 are provided with depending portions forming relatively broad surfaces at the free ends of these arms. This prevents arm 6 from passing beneath arm 5 when shaft 7 is rocked into stop closing direction, it being understood that turning of this shaft in stop closing direction is 50 positively limited by contact of stops 16 with the rail sections. Turning of shaft 22 in stop closing direction is positively limited by con-

tact of stops 25 with the rails so that, during the dumping operation arm 28 is completely out of contact with arm 27. This feature is of importance as, at this time, track section G is completely disconnected 55 from the rest of the feeder apparatus thus permitting accurate weighing of the loaded car on section G. Upon return of the dump to loading position, shaft 1 is again rocked in a counter-clockwise direction, as considered in Fig. 3, thus opening stops 25 to permit the loaded car which has been weighed to run onto the dump. This rocking of the shaft also serves to depress arm 5 below arm 6, at which time shaft 7 is 60 projected by spring 9 so as to position arm 6 above arm 5, the stops 16 remaining closed, as in Fig. 1. The dump A is then tilted by the loaded car and the operation previously described is repeated. This provides simple and highly efficient means whereby the loaded cars are cut out of the trip, weighed during the dumping operation, and then fed onto the dump upon return of the 65 same to loading position. While I have described the apparatus as used for weighing and feeding cars singly, it can be readily adapted to cut out and feed any number of cars desired by altering the positions of stops 16 and trip lever 20, and lengthening 70 track sections F and G.

75 As the cars are cut out and weighed during the dumping operation this apparatus avoids any loss of time in feeding and permits the cars to be weighed and fed onto the dump as fast as it can be operated. This results in maximum capacity which is of great importance in the use of feeders to dumps or cages.

80 In Fig. 7 I have illustrated the manner in which the apparatus is used with a rotary dump. The dump D, of any suitable or preferred type, is provided with a guide ring 30 having a channel 31 which receives pin 3 of trip arm 4. Ring 30 is provided with a cam element 30^a disposed to move pin 3 in proper direction for opening stops 25 as the dump comes into loading position. As the dump turns from loading position, pin 3 leaves cam portion 30^a of the slot and enters the main portion of slot 30 so as to be raised thereby and held in this position against the tension of spring 12 until after the stops 16 have been released and closed. 85 As the dump again returns to loading position the pin 3 is depressed rocking shaft 1 so as to feed another car onto the dump, and the operation is repeated during rotation of the dump as previously described in connection with the tilting dump.

90 If desired, the ring 30 may be replaced by a suitable cam positioned to strike pin 3 and open stops 25, this acting to rock shaft 1 in the opposite direction to open stops 16 95 and permit closing of stops 25 as the dump

starts to turn into dumping position. This is an obvious modification or variation of the form illustrated in Fig. 7 and need not be further described in detail or illustrated.

5 I consider it an important feature of my invention that the stops 26 are opened by shaft 1 and associated parts as the dump is turned into dumping position with a loaded car. In actual practice, stops 16 will 10 frequently have to hold back heavy trips composed of many loaded cars, so that great pressure is exerted on these stops. Under such conditions, it would be doubtful if the stops could be opened by the action 15 of a dump returning to loading position with an empty car or cars. But this danger is avoided by having the dump rock shaft 1 in the direction to open stops 16 when the dump is turning into dumping position with 20 loaded cars on the dump, due to the inertia of the loaded cars. Also, the weight 26, which is preferably considerably heavier than the weights commonly used for this 25 purpose, is of material assistance in initiating the rocking movement of shaft 1 in proper direction to open stops 16, which is also an important feature of my invention.

What I claim is:—

1. In an apparatus of the character described, in combination with a dump including a track section for reception of a car and an approach track leading to the dump, said approach track including a relatively movable section, means for holding a trip 30 of cars above the movable section, means for holding a car on said section, means for releasing the car on said movable track section when the dump is returned to loading position after a dumping operation, said means 35 for releasing the car holding means on the movable track section and permitting resetting thereof and also releasing the trip of cars above the movable section upon movement 40 of the dump into dumping position, means for setting the car trip holding means, and means for disconnecting said trip holding 45 means from the releasing means when a predetermined number of cars have been fed onto said movable track section.

50 2. In an apparatus of the character described, in combination with a dump including a track section for reception of a car and an approach track leading to the dump, said approach track including a relatively 55 movable section, stops on said movable section, trip stops on the approach track above the movable section, means for closing the first mentioned stops, means for closing the second mentioned stops, dump actuated 60 means for opening the movable section stops upon return of the dump to loading position, said dump actuated means releasing the movable section stops to permit closing thereof and opening the trip 65 stops upon movement of the dump into

dumping position, and means for releasing the trip stops to permit closing thereof when a predetermined number of cars have been fed onto the movable track section.

3. In an apparatus of the character described, in combination with a dump including a track section for reception of a car and an approach track leading to the dump, said approach track including a relatively movable section, stops on said movable section, trip stops on the approach track above the movable section, means for closing the first mentioned stops, means for closing the second mentioned stops, dump actuated 70 means for opening the movable section stops upon return of the dump to loading position, said dump actuated means being completely disconnected from the movable section stops and opening the trip stops 75 upon movement of the dump into dumping position, and means for releasing the trip stops to permit closing thereof when a predetermined number of cars have been fed onto the movable track section.

4. In an apparatus of the character described, in combination with a dump including a track section for reception of a car and an approach track leading to the dump, said approach track including a relatively movable section, stops on the movable section, trip holding stops on the track above said movable section, means for closing the movable section stops, means for closing the trip stops, a rockably mounted shaft extending across and detached from the movable track section, means for turning the shaft in one direction when the dump is turned into dumping position and in the other direction when the dump is returned to loading position, members connected to the shaft and the movable section stops and co-operating to open the same when the shaft is turned in the second direction, said members being completely disengaged when the shaft is turned in the first direction, members connected to said shaft and the trip stops and cooperating to open the same when the shaft is turned in said first direction, and means for disengaging the second mentioned members to permit closing of the trip stops after a predetermined number of cars have been fed onto the movable track section.

5. In an apparatus of the character described, in combination with a dump including a track section for reception of a car and an approach track leading to the dump, said approach track including a relatively movable section, stops on the movable section, trip holding stops on the track above said movable section, means for closing the movable section stops, means for closing the trip stops, a rockably mounted shaft extending across and detached from the movable track section, means for turning the shaft in one direction when the dump is turned into

dumping position and in the other direction when the dump is returned to loading position, members connected to the shaft and the movable section stops and co-operating to open the same when the shaft is turned in the second direction, said members being completely disengaged when the shaft is turned in the first direction, members connected to said shaft and the trip stops and cooperating to open the same when the shaft is turned in said first direction, and car actuated means for disengaging the second mentioned members to permit closing of the trip stops after a predetermined number of cars have been fed onto the movable track section.

6. In an apparatus of the character described, in combination with an approach track, a main rock shaft, a supplemental rock shaft, stops on the track, connections between the stops and the supplemental shaft for closing and opening the former in accordance with turning of the latter, means for turning said supplemental shaft in stop closing direction, a counter shaft rockably mounted beyond the supplemental rock shaft, stops on the track beyond the first mentioned stops, connections between the counter shaft and the second mentioned stops for opening and closing the latter in accordance with rocking of the latter, means for rocking the counter shaft in stop closing direction, cooperating members carried by the main shaft and the supplemental shaft for rocking the latter in stop opening direction when the main shaft is rocked in one direction, cooperating members carried by the main shaft and the counter shaft for rocking the latter in stop opening direction when the main shaft is turned in the other direction, said counter shaft having endwise movement, means for normally holding the counter shaft in endwise position with the member carried thereby in operative relation to the cooperating member of the main shaft, and car actuated means beyond the stops connected to the counter shaft for retracting said counter shaft to disengage the member carried thereby from the cooperating member carried by said main shaft.

7. In an apparatus of the character described, an approach track including a fixed section and a relatively movable section, stops on said movable section, stops on the fixed section above said movable section, a main rock shaft, means for normally holding the stops on the fixed track

section closed, means for normally holding the stops on the movable section closed, means for opening the stops on said movable track section when the shaft is rocked in one direction, said means being detached from the parts carried by the movable track section to permit free movement thereof when the shaft is rocked in the other direction and the stops on said movable section are closed, means for opening the stops on the fixed track when the shaft is rocked in said other direction, and means for releasing the stops on the fixed section to permit closing thereof when a loaded car passes therefrom onto the movable section.

8. In an apparatus of the character described, a dump, an approach track leading thereto, lower stops on the track, trip holding stops above the lower stops, means for closing the trip holding stops, means for closing the lower stops, means for opening both sets of stops, the last mentioned means being actuated by the dump to open the lower stops as the dump approaches loading position and to open the trip holding stops after the dump receives a loaded car and starts turning into dumping position, the lower stops being released to permit closing of the same as the dump turns into dumping position, and means for releasing the trip holding stops to permit closing thereof after a car has passed from the trip beyond the trip holding stops.

9. In an apparatus of the character described, a dump, an approach track leading thereto, lower stops on the track, trip holding stops above the lower stops, means for closing the trip holding stops, means for closing the lower stops, means for opening both sets of stops, the last mentioned means being actuated by the dump to open the lower stops as the dump approaches loading position and to open the trip holding stops after the dump receives a loaded car and starts turning into dumping position, the lower stops being released to permit closing of the same as the dump turns into dumping position, the means for closing the lower stops assisting in initiating operation of the said last mentioned means in trip holding stop opening direction, and means for releasing the trip holding stops to permit closing thereof after a car has passed from the trip beyond the trip holding stops.

In testimony whereof I affix my signature.

JAMES A. NOLAN.
